(No Model.)

J. S. CASE.

HEATING RAILWAY TRAINS.

No. 366,761.

Patented July 19, 1887.

UNITED STATES PATENT OFFICE.

JOSEPH S. CASE, OF NEW YORK, N. Y.

HEATING RAILWAY-TRAINS.

SPECIFICATION forming part of Letters Patent No. 366,761, dated July 19, 1887.

Application filed February 8, 1887. Serial No. 226,896. (No model.)

To all whom it may concern:

Be it known that I, JOSEPH S. CASE, of the city and State of New York, have invented an Improvement in Heating Railway-Trains, 5 of which the following is a specification.

Railway-trains have been heated by steam taken from the boiler of the locomotive and carried through radiating-pipes within the cars, there being flexible tubular connections 10 between the respective cars. In some instances the steam-generator has been placed in the baggage-car, and in other instances a heater for hot air has been located in the tender. All these arrangements are objectionable in one 15 or more particulars. Where the steam is taken from the locomotive-boiler, the supply of steam is often insufficient, especially in very cold weather, and the cars are not properly warmed and the locomotive is not adequately supplied with steam. Where the 20 steam-boiler for the heating apparatus is in the baggage-car, there is risk of fire if the car is upset, as in case of collision; and with a heater in the tender for hot air to be supplied 25 to the cars there is difficulty in causing the same to circulate, and a blower driven by the locomotive has to be resorted to.

My improvement relates to a steam-boiler placed in the tender, having a furnace-chamber that is to be supplied with fuel by the fireman, and there is a cock and connections from the steam-space of the boiler to coupling-pipes and radiating-pipes within the cars, and the steam-boiler is below a hood, forming an 35 inclined floor to the coal-bunker of the tender. By this improvement the warming apparatus is in the care of the fireman and the tender is utilized for the steam-heating boiler, and the risk of fire in cases of collision is avoided, be- 40 cause the parts of the tender are almost all of iron and not liable to catch fire, and besides this, the water-tank in the tender surrounds the heater and furnishes an additional protection.

45 In the drawings, Figure 1 is a vertical section illustrating my improvement, and Fig. 2 is a plan view.

The tender is of any usual or desired construction, and it is provided with the floor or 50 platform A and the water-tank B, that forms the sides and back of the tender, and there are wheels at C.

The steam-heater is of suitable size and shape. It is shown at D with a flue-boiler and a fire-chamber, 2, the door 3 of which is 55 above the floor of the tender, and the grate-bars 12 and the ash-pit 13 are below the floor. The smoke-box and smoke-stack 6 are preferably at the back end, as shown. The steam from the upper part or dome of the boiler is 60 taken off by a pipe and cock, 7, to the cars of the train, there being a flexible tubular connection, 9, between the cock 7 and the first car and also between one car and the next, and there are any suitable radiators or radia- 65 tor-pipes within the cars for heating the same. The smoke-stack should slip into or upon a base-ring, so as to be taken off during summer, when the heater is not required.

Above the boiler D there is a hood, K, preferably of boiler-iron; and said hood is curved 70 downwardly between the sides of the boiler and the water-tank to support the coal and to form inclines or chutes to cause the coal to run forward toward the place where the same is 75 shoveled by the fireman, and there is to be a vertical or flaring guard over the boiler, as seen at L, to prevent the coal falling over in front of the fire-door 3.

The sides of the tender are preferably made 80 sufficiently high to maintain the required coal-space and offset the loss of fuel-space occasioned by raising the floor of the coal-bunker.

In introducing my improvements the coal in the tender is raised rather higher than usual; 85 but otherwise the capacity of the tender is not interfered with or lessened, and all the conveniences of the ordinary tender are preserved, and the heating of the train is performed with reliability and without loss of 90 time and without risk of fire in case of collisions or the upsetting of the cars from any cause.

The steam-heating boiler is to be fed with water from the tender in any suitable manner; 95 and I also provide a pipe, H, leading from the boiler of the locomotive to the boiler D, with cocks or valves in such pipe, so that the cars may be warmed up by steam from the locomotive-boiler in cases where the heat is only 100 required occasionally, thereby avoiding the necessity of kindling a fire in the boiler D and allowing for using the steam from the locomotive-boiler when there is a surplus of the

same without disturbing the connections; and when steam is run through the boiler D and there is a fire in the furnace thereof the steam becomes superheated and more efficient in heating the cars.

5 In consequence of the steam-boiler D in the tender being connected to the locomotive by the pipe H and cocks, the steam generated in such boiler D can be passed to the locomotive in 10 case of necessity, as well as the steam from the locomotive being used, if needed, in heating.

I claim as my invention—

The combination, in a tender, of the steam-

boiler within the tender and between the water-tank sides, the hood over the boiler, the 15 shield for supporting the fuel, the steam-pipe and cock from the boiler, and the flexible connection to the pipes or radiators within the cars, substantially as set forth.

Signed by me this 3d day of February, A. 20
D. 1887.

JOS. S. CASE.
